UNITED STATES PATENT OFFICE.

JOSEPH JEAN GRÉGOIRE, OF HOLLYWOOD, CALIFORNIA.

INTERNAL-COMBUSTION ENGINE.

Application filed October 26, 1926. Serial No. 144,294.

The present invention relates to an internal combustion engine preferably of the four cycle type and its object is to provide a valve mechanism for engines of this type which shall effectively control the ignition and exhaust, which shall operate noiselessly, and which shall conduce to the obtaining of maximum efficiency.

Another important object of the invention lies in the provision of a valve mechanism which is simple in its construction, reliable in its operation, inexpensive to manufacture, and otherwise well adapted to the purpose for which it is designed.

With the above and numerous other objects in view, as will appear as the description proceeds, the invention resides in certain novel features of construction, and in the combination and arrangement of parts as will be hereinafter more fully described and claimed.

In the drawings:

Figure 1 is a sectional side elevation of an engine embodying the features of my invention,

Fig. 2 is a vertical transverse section therethrough,

Fig. 3 is a detailed perspective of one of the slide valves,

Referring to the drawing in detail, it will be seen that the numeral 5 denotes a crank case on which is bolted a cylinder block containing a plurality of cylinders 6. The cylinder block may be of any conventional formation but is herein shown as having an integral head in which are mounted the usual spark plugs 7. The cylinder block has a water jacket 8 associated therewith and has also the head. It is to be noted that on the side of the cylinder block there are provided a plurality of slide ways 9 which are disposed vertically, there being two slide ways for each cylinder. Each cylinder is also provided with two ports 10 which lead into the upper portions of the slide ways. The pistons in the cylinder 6 are denoted by the numerals 11 and have the usual connecting rods 12 associated therewith and associated with a crank shaft 14 on which is fixed a gear 15 meshing with another gear 16 which operates a second or auxiliary crank shaft 17 one-fourth crank shaft speed. Connecting rods 18 are engaged with the cranks of the auxiliary crank shaft 17 and extend through the openings 19 in the crank shaft upwardly alongside of the engine blocks.

Slide valves V are slidably mounted in the slide-ways 9. Each valve V includes a flat bar-like body 20 which is provided at its lower end with a pair of elongated loops 21 in extensions thereof. The connecting rods 18 are provided with laterally extending pins 22 which extend into the loops 21 so as to provide a lost-motion connection between the connecting rods and the valves. The intake manifold is denoted by the numeral 23 and the exhaust manifold by the numeral 24. The valve mechanism will be timed to fire the cylinders in any preferred manner. As will be quite apparent to those skilled in the art as the piston 11 moves downwardly on its intake stroke, the exhaust valve will be closed and the intake valve opened. As the piston moves upwardly on its compression stroke, both valves will be closed. The firing then takes place and the piston proceeds downwardly on its power stroke with both valves closed and as it moves upwardly on its exhaust stroke the exhaust valve will open and the intake valve remain closed. The valves only move when the pin 22 engages the top or bottom of the loops 21. It is to be understood that the connecting rods extend between these loops. This lost motion connection is very important in that it allows the valves to remain open a predetermined length of time and allows them to remain closed to be opened only at the proper interval of time. This lost motion also enables the valve to be constructed as is shown in the drawings so that they do not move above the cylinder head as would be necessary otherwise. The valves are held frictionally in the slide-ways by a cover plate 26 which also extends downwardly to be engaged with the crank case so as to prevent the dirt getting through the openings 19.

It is thought that the construction, operation, and advantages of this invention will now be clearly understood by those skilled in this art without a more detailed description thereof. The present embodiment of the invention has been disclosed in detail merely by way of example since in actual practice, it attains the features of advantage enumerated as desirable in the statement of the invention and the above description. It will be quite apparent however, that numerous changes in the details of construction, and in the combination and arrangement of parts may be resorted to with-

out departing from the spirit or scope of the invention as hereinafter claimed or sacrificing any of its advantages.

Having thus described my invention what

6 I claim as new is:

1. In an internal combustion engine, the combination of a cylinder having a vertical slide-way on the exterior thereof, a valve including a bar-like body having extending 10 from one end thereof a pair of loops, a crank shaft for the operation of said valve, a connecting rod engaged with said crank shaft and having a laterally extending pin at one end, said one end extending between 15 the loops with the pin ridable in the loops so as to form a lost-motion connection between the crank shaft and the valve to transfer the rotary motion of the crank shaft into vertical rectilinear motion of the valve for the purpose of closing and opening in-

termittently a port provided in the cylinder.

2. An internal combustion engine of the class described, including, in combination, a cylinder, a piston in the cylinder, a crank shaft, means for connecting the crank shaft 25 with the piston, a second crank shaft, means connecting the crank shaft so that the second crank shaft will rotate at one-fourth crank shaft speed, said cylinder provided with slide-ways and ports communicating therewith, valves slideable in the slide-ways, each valve including a bar-like body and having its lower ends provided with a pair of spaced parallel elongated loops, connecting rods associated with the second crank 30 shaft and having transversely extending pins ridable in the loops.

In testimony whereof I affix my signature.

JOSEPH JEAN GRÉGOIRE.
